UNITED STATES PATENT OFFICE.

WILLIAM J. WIRT, OF BRECKENRIDGE, MINNESOTA.

AUTOMATIC TRAIN-STOP MEANS.

1,406,797.

Specification of Letters Patent. Patented Feb. 14, 1922.

Application filed July 9, 1921. Serial No. 483,589.

To all whom it may concern:

Be it known that I, WILLIAM J. WIRT, a citizen of the United States, residing at Breckenridge, in the county of Wilkin and 5 State of Minnesota, have invented new and useful Improvements in Automatic Train-Stop Means, of which the following is a specification.

The object of my present invention is the 10 provision of simple, reliable and otherwise advantageous means for automatically applying the fluid pressure brakes of a train and stopping the train with a view to precluding the same running by a block signal 15 in darkness or fog.

To the attainment of the foregoing, the invention consists in the improvement as hereinafter described and definitely claimed.

In the accompanying drawings, forming 20 part of this specification:—

Figure 1 is a plan view showing the track portion of my improvement.

Figure 2 is a longitudinal vertical section on an enlarged scale taken in the plane 25 indicated by the line 2—2 of Figure 1.

Figure 2^a is a detail side elevation showing the relative arrangement of the locomotive equipment and the tappet shoe for actuating the locomotive equipment.

30 Fig. 2^b is a cross sectional view taken on the line 2^b of Fig. 2.

Figure 3 is a side elevation of the locomotive equipment comprised in my improvement.

35 Figure 4 is an end elevation of said equipment.

Figure 5 is a longitudinal vertical section of the equipment.

Figure 6 is a cross section of the same.

40 Figure 7 is an inverted plan view of the locomotive equipment.

Figure 8 is a top plan view of the same.

Similar numerals of reference designate corresponding parts in all of the views of

45 the drawings.

In accordance with my invention I arrange midway between the rails 1 of a railway a casing 2 in which is longitudinally disposed a vertically movable tappet shoe 3, 50 the end portions of which are inclined, as indicated by 4. Normally the upper surface of the tappet shoe 3 rests about four inches above the upper surfaces of the rails 1, and the shoe 3 is yieldingly maintained 55 in the said normal position by springs 5, arranged in the casing 2 and under the

tappet shoe 3 as clearly shown in Figure 2. In virtue of this yielding support of the tappet shoe 3 snow and ice are effectively prevented from holding the shoe 3 down, 60 and from preventing downward movement of the shoe when the same is unlocked. In this latter connection I would have it understood that when a signal is set against an approaching train the shoe 3 will be 65 locked in its upper working position through the medium of the mechanism best shown in Figures 2 and 2^a and hereinafter explicitly described. Manifestly when the shoe 3 is free to move downwardly against 70 the action of the springs 5 the said shoe 3 will not operate the valve mechanism complementary to the locomotive to a train.

The locomotive equipment of my improvement comprises a casing body 6, an apertured plate 7 bolted to the lower side of the casing body 6, and a sub-casing 8 arranged above the casing body 6. Movable vertically and rectilinearly in the plate 7 and casing body 6 and held at 9 against 75 turning about its axis is a plunger 10 on the upper end of which is an upwardly extending rod 11. The said plunger 10 is strongly though yieldingly held against upward movement by springs 12 housed in the 80 casing body 6, and its lower end is rounded as indicated by 13 so as to enable it to better pass through snow and ice and to better engage or be engaged by the tappet shoe 3. The said lower end of the plunger 90 10 is preferably arranged so as to clear the tops of the rails about two or three inches when the plunger is in its normal position. Manifestly when the plunger 10 engages and slides upwardly on one end of 95 the shoe 3, the plunger will be moved upwardly provided the shoe 3 is locked against downward movement under the condition before indicated. If, however, the shoe 3 is unlocked, the springs 12 above the plunger 10 are sufficiently strong to enable the 100 said plunger 10 to depress the shoe 3 so that no operation of the brakes on the train will ensue.

In accordance with my invention a trigger 105 valve 20 is arranged in the sub-casing 8 in position to be opened by upward movement of the plunger portion 11, Figure 5, and an air pipe 21 leads from an engineer's valve (not shown) to the said trigger valve 21. 110 In this connection it will be understood that my locomotive equipment is disposed be-

ween the engineer's valve and the train pipe so as to cut off control of the air by the engineer, though it will be understood in this connection that after the application of the brakes through the medium of my improvement, the engineer can proceed under the locomotive and close the trigger valve 20. The port for vending air from the train pipe to the atmosphere is indicated by 23 in Figures 3 and 5. In virtue of the relative arrangement of the elements as shown in Figure 5 the trigger valve 20 is thrown into open position by upward movement of the plunger portion 11, and the trigger valve 20 remains in the said open position notwithstanding subsequent downward movement of the plunger 10. It will also be understood that it is desirable to arrange the locomotive equipment in the longitudinal center of the locomotive so that said equipment will co-operate with the tappet shoe 3 irrespective of the direction in which the train is moving.

In the practical operation of my invention it will be understood that when a signal 25 is set against an approaching train, the tappet shoe 3 will be locked in its upper position, and therefore when the plunger 10 of the train encounters the said shoe 3 the shoe will operate to positively move the plunger 10 upwardly whereupon the plunger portion 11 30 will open the trigger valve 20. The trigger valve 20 will remain open notwithstanding the movement of the plunger 10 off the shoe 3, and consequently the train will be brought to a gradual stop. After the stopping of the train as before indicated it is incumbent 35 on the engineer to descend and gain access to the trigger valve 20 and close the same whereupon the brake will be adapted to operate under the control of the engineer in 40 the ordinary well known manner.

Notwithstanding my improvement may be depended upon to automatically stop a train in the manner described, it will be observed that the improvement is simple 45 and inexpensive and is adapted to be installed in railways and locomotives such as at present in use at small expense.

I have entered into a detailed description of the construction and relative arrangement of parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made such as fall within the scope of my invention as defined in my appended claim.

Having described my invention, what I claim and desire to secure by Letters Patent, is:—

In automatic train stop means, the 65 combination of a casing adapted to be carried by a locomotive or car, a sub-casing arranged above the first-named casing, a trigger valve arranged in the sub-casing and adapted when opened to exhaust air under pressure from a train pipe to the atmosphere, a rectilinearly movable plunger guided and held against turning about its axis in the first-named casing and having an upwardly extending portion adapted on 70 upward movement of the plunger to open the trigger valve, and strong spring means relatively arranged to yieldingly hold the plunger against upward movement.

In testimony whereof I affix my signature. 80

WILLIAM J. WIRT.
